FOUNDATION GARMENT OR THE LIKE

Philip H. Robbins, New York, N. Y., assignor to
Poirette Corsets, Inc., New York, N. Y.

Application April 16, 1940, Serial No. 329,948

14 Claims. (Cl. 2-37)

This invention relates to a foundation garment for women's wear.

A garment, in accordance with this invention is in the form of a girdle-like structure comprising an upper portion for encompassing the wearer's body at the waist and above the latter to near the busts and a lower portion for encompassing the hips, thighs, abdomen, lower portion of the back and buttocks and said type of garment is termed by the trade a foundation garment, or it may be the form aforesaid having attached to its upper end a brassière.

The garment as hereinafter set forth is an improvement upon the foundation garment as disclosed by Letters Patent 2,137,182 granted to me November 15, 1938, and it not only embodies all of the aims and the advantages as set forth by the Letters Patent aforesaid, but further aims to provide, in a manner as hereinafter set forth, a foundation garment including a pair of fashioned webs of elastic woven fabric forming the sides of the body structure aforesaid, each web having connected thereto a carrier of elastic woven fabric possessing the same characteristic as the web, and with each carrier having secured thereon a pair of oppositely disposed sets of spaced elastic members for creating resistance to the expansive action of the carriers and also the webs resulting in additional fashioning for the garment.

The invention further aims to provide, in a manner as hereinafter set forth, a foundation garment including elastic webs, elastic carriers opposing and connected to the webs and spaced restraining elastic means carried by and secured to the carriers and with said webs, carriers and means correlating for imparting a thoroughly efficient restraining and controlling power for the garment when the latter is worn.

The invention further aims to provide, in a manner as hereinafter set forth, a foundation garment whereby the elastic carriers and the spaced elastic restraining means aforesaid are concealed with respect to the outer face of the garment when the latter is worn.

The invention further aims to provide a foundation garment with an elastic gusset, elastic webs spaced from the gusset and having correlated therewith elastic carriers provided with elastic restraining means and with said gusset, webs, carriers and means so constructed and arranged to thereby provide when the garment is worn to control the diaphragm, waist line and the abdomen, as well as the fatty tissues of the side and back muscles of the hips, resulting in

the garment being held firmly in place, snugly fitting and preventing it from riding up on the body of the wearer.

The invention further aims to provide, in a manner as hereinafter set forth, a garment which is simple in its construction and arrangement, strong, durable, compact, thoroughly efficient for the purpose intended thereby, readily assembled, pleasing in appearance and comparatively inexpensive to manufacture.

To the above ends essentially and others which may hereinafter appear, the invention consists of the novel construction, combination and arrangement of parts as will be more specifically described and illustrated in the accompanying drawings, wherein are shown embodiments of the invention, but it is to be understood that changes, variations and modifications may be resorted to which fall within the scope of the invention as claimed.

In the drawings:

Figure 1 is a perspective view of a foundation garment, in accordance with this invention as applied to the simulation of the body of a wearer,

Figure 2 is an elevation looking towards the outer face of the garment with the body of the latter split from top to bottom and extended,

Figure 3 is a view similar to Figure 2 looking towards the inner face of the garment,

Figure 4 is a section on line 4-4 Figure 3 upon an enlarged scale,

Figure 5 is a section on line 5-5 Figure 3 and upon an enlarged scale,

Figure 6 is a section on line 6-6 Figure 3 and upon an enlarged scale,

Figure 7 is a front elevation of the front part of the garment,

Figure 8 is a section on line 8-8 Figure 7, and

Figure 9 is a section on line 9-9 Figure 3.

The garment, generally indicated at 10 will be in the form of an endless girdle-like body which is formed with a slit 11 in one of its sides opening at the top edge thereof. Arranged within the body of the garment 10 is a non-elastic flap

12 for extension across the slit 11. That face of flap 12 which opposes the body of the wearer is formed of soft yieldable material. The flap 12 in proximity to one of its side edges is secured by stitching, as at 13, to the body of the garment in proximity to one of the edges of the slit 10. The flap 12 at its lower end is secured by stitching, as at 13a, to the body of the garment below the slit 11. The inner face of the body of the garment in proximity to the other edge of the slit has secured thereto spaced eyes 14. The flap 12 has

secured to its front face, between its side edges, hooks 15 for correlation with the eyes 14 for connecting the flap to said body in a position extending across the slit 11. The body of the garment has secured thereto a slide fastener structure 16 of known form for connecting the edges of the slit 11 together. The structure 16 is operated from the outer face of that side of the garment formed with the slit 11.

The garment 10 includes a front part 17, a 10 non-split side part 18, a split side part 19 and a back part 20. The front part is formed of an outer or facing section 21, an inner section 22 and a gusset 23. The sections 21 and 22 are of like contour and each includes a pair of non-elastic oppositely disposed fabric strips having their inner side edges formed with straight upper edge portions 24, outwardly curved intermediate portions 25 and lower edge portions 26 which incline outwardly from the upper to their lower ends with respect to the lower ends of the edge portions 25. The edge portions 25 and 26 of the strips, which provide the sections 21 and 22, correlate to form the front part 17, centrally of its lower portion with an inverted substantially V-shaped opening 27, which opens at the bottom edge of said front part 17. Disposed between the sections 21 and 22 and extending completely across that part of the opening 27 arranged between the edge portions 25 is the gusset 23 which is formed of elastic material having its bottom edge aligned with the upper ends of the edge portions 26. The gusset 23 is secured to the sections 21, 22 of the front part 17 by the stitching 28. The latter also secures the sections 21, 22 of front part 17 together. The strips of each section are secured together at their edge portions 24 by the stitching 29. The latter also secures the strips of one section to the strips of the other section. The outer side edges 30 of the sections 21, 22 are substantially of compound curvature. The said sections 21, 22 are of a length to extend from the bottom to the top edge of the garment. Preferably the section 21 will be formed from satin and the section 22 of dull silk, but it is to be understood that said sections 21, 22 may be formed of any character of non-elastic fabric desired. Extending across the upper marginal portion of that face of section 22, which opposes the wearer, is a non-elastic reinforcement 31 of tape-like form secured to said section 22 by stitching 31a. The latter is disposed in a manner relative to said section 22 and reinforcement 31 to form a pair of spaced aligned pockets 32 closed at their upper ends and open at their lower ends. Secured to that face of the section 22, which opposes the wearer by suitable stitching, is a pair of aligned spaced parallel pocket forming members 33 which are open at their upper ends. The lower open ends of the pockets 32 align with, open into and abut the open upper ends of the members 33. Arranged in the members 33 and extending from the upper ends of such members into the pockets 32 are stays 34. The faces of the members 33, which oppose the wearer, are to be in the form of soft yieldable material. The members 33 are of less length than the section 22 and are closed at their lower ends. The stays 34 are of less length than and have their lower ends arranged above the lower ends of the members 33. A stitching 35 is correlated with each member 33 to maintain the lower end of a stay 34 above the lower end of a member 33. The lower marginal portions of the rear face

of the strips which form the section 22 have secured thereto non-elastic reinforcements 36 in the form of tape. The lower marginal portion of the inner face of the gusset 23 has secured 5 thereto a tape-like elastic reinforcement 37.

The back part 20 consists of an outer and an inner section 38, 39 respectively of like form. The said back sections are formed of non-elastic fabric webs. Preferably the outer section will be of satin and the inner section of dull silk, but it is to be understood that the sections 38, 39 may be formed of any suitable non-elastic fabric. There is arranged against and throughout the upper and lower marginal portions of that face 15 of section 39, which is to oppose the wearer, non-elastic reinforcements 40, 41 respectively of tape-like form which are secured to the sections 38, 39 by the stitchings 42, 43 respectively. The stitchings 42, 43 not only secure the reinforcements to 20 back part 20, but also secure the sections 38, 39 of such part together. The stitching 42 for the reinforcement 40 is so disposed relative to the latter and the section 39 to form back part 20 with a pair of spaced aligned pockets 44 closed 25 at their upper ends and open at their lower ends. Secured by stitching to that face of section 39, which is to oppose the wearer, is a pair of spaced parallel pocket forming members 45 closed at their lower ends and open at their upper ends. 30 The open lower ends of the pockets 44 align and communicate with the upper open ends of the members 45. Arranged in the members 45 and extending into the pockets 44 are stay members 46. The faces of the members 45, which are to 35 oppose the wearer, will be formed of soft yieldable material.

The side part 18 includes outer and inner sections 47, 48 respectively of like length which are flush at their upper ends. The section 47 is 40 formed of a pair of webs 50. The section 48 is formed of a pair of webs 51. The said webs are fashioned and formed of elastic woven material of the desired length and width, and when the garment is worn are disposed on their lower end edges. The webs of each pair are of like form and have their inner side edges 52 aligned throughout. The inner side edges of the webs of one pair are aligned throughout with the inner side edges of the other pair. The inner side marginal portion of that face, which is to oppose the wearer, of each of the webs 51 of the inner section has secured thereto, by stitching 52a, an elastic reinforcing member 53 of tape-like form extending from the lower end to the upper end 55 of the web. The inner side edges 52 of the webs 50 are secured to the inner side edges 52 of the webs 51 by stitching 54. The outer side edge of a web 50 and a web 51 are arranged between the sections of the front part 17, at one side of the latter and are secured to said front part 17 by the stitching 55. The outer side edge of the other web 50 and the other web 51 are arranged between the sections of the back part 20, at one side of the latter and are secured to said back part 20 by the stitching 56. There is common to the webs 51 an elastic reinforcing member 57, of tape-like form which is arranged against the lower marginal portion of the faces of the webs 51 which are to oppose the wearer. The member 57 is secured to the webs 51 by the stitching 58. The stitchings 52a and the stitching 58 connect the webs 50 to the webs 51.

The inner section 48 of the side part 18 includes a pair of oppositely disposed webs 59, 60 of elastic woven material corresponding in width

to and of less length than a web 50 or a web 51. The web 59 is of less length than the web 60. The width of webs 59, 60 correspond substantially to the width of a web 50 or 51. The length of the webs 59, 60 is materially less than the length of a web 50 or 51. The lower end of the web 59 inclines downwardly and outwardly. The lower end of the web 60 inclines downwardly and outwardly, but the inclination of the lower end of web 60 is greater than the inclination of the lower end of web 59. The material from which the webs 59, 60 are formed corresponds to the material of the webs 50, 51. The webs 59, 60 align with the upper ends of the webs 50, 51. The web 60 depends below the web 59.

There is correlated with the web 59 a set of spaced elastic combined fashioning and resistance increasing members of tape-like form which are disposed on that face of web 59 which is to oppose the wearer. The number of members of the set is four and are designated at 61, 62, 63, 64. The members of said set are secured to the web 59 by zig-zag stitching 65 and extend from the inner to the outer side edge of the web. The member 63 is disposed horizontally. The member 64 is arranged below the member 63 and extends at a downward inclination from the inner to the outer side edge of and has its bottom edge flush with the lower end of the web. The member 62 is arranged directly over the member 63 and inclines upwardly from the inner side edge to the outer side edge of the web. The member 61 is arranged directly over the member 62 and inclines upwardly from the inner side edge to the outer side edge of and is disposed in spaced relation to the top edge of the web. That face of the web 59 provided with the elastic members has arranged throughout the upper marginal portion thereof an elastic reinforcement 65^a of tape-like form spaced from the member 61. The reinforcement 65^a is secured to web 59 by stitching 66 and the latter also acts to secure the upper portions of a web 50, a web 51 and the web 59 together. The outer side edge of web 59 and the outer ends of the elastic members are disposed between the sections 21, 22 of the front part 17 at one side of the latter and are secured to the front part 17 by the stitching 55. The inner side of web 59 and the inner ends of the elastic members are arranged between the upper portion of a web 51 and the upper portion of a reinforcing member 53 and which are secured to the said web and member by a stitching 52^a. The lower end edge of the web 59 is free.

There is correlated with that face of the web 60, which is to oppose the wearer, a set of spaced elastic combined fashioning and resistance increasing members of tape-like form, which is oppositely disposed with respect to the other set of members referred to. The number of the set of members correlated with the web 60 is four and are designated at 67, 68, 69, 70, are secured to the web 60 by zig-zag stitching 71 and extend from the inner side edge to the outer side edge of web 60. The member 67 is disposed horizontally and arranged in proximity to the upper end of web 60. The member 68 is positioned directly below member 67 and extends at a downward inclination from its inner to its outer end. The member 69 is arranged directly below the member 68 and extends at a downward inclination from its inner to its outer end and the member 70 is arranged directly below the member 69 and extends at a downward in-

clination from its inner to its outer end. The inclination of member 69 is greater than the inclination of member 68, and the inclination of member 70 is greater than the inclination of member 69. That face of the web 60 provided with the elastic members has arranged throughout the upper marginal portion thereof an elastic reinforcement 72 of tape-like form spaced from the member 67. The reinforcement 72 is secured to web 60 by stitching 73 and the latter also acts to secure the other webs 50, 51 and the web 60 together. The outer side edge of web 60 and the outer ends of the elastic members 61, 62, 69, 70 are disposed between the sections 38, 39 of the back part 20 at one side of the latter and are secured to said part 20 by the stitching 56. The inner side edge of web 60 and the inner ends of the elastic members 67, 68, 69, 70 are arranged between the upper portion of the other web 51 and the upper portion of the other reinforcing member 53 and which are secured to such web and such member by the other stitching 52^a. The lower end edge of web 60 is free. Bridging the upper portion of the joint between the webs 50, 51 and 59, 60 and secured to that face of side part 18, which is to oppose the wearer, is a casing 74 of cushioning material carrying a stay 75.

The side part 19 includes outer and inner sections 76, 77 respectively of like length and which are flush at their upper ends. The section 76 is formed of a pair of webs 78. The section 77 is formed of a pair of webs 79. The said webs are fashioned and formed of elastic woven material of the desired length and width and when the garment is formed are disposed on their lower end edges. The webs of each pair are of like form and have their inner side edges 80 aligned throughout. The inner side marginal portions of that face, which is to oppose the wearer, of each of the webs 79 of the inner section 77 has secured thereto, by stitching 81, an elastic reinforcing member 82 of tape-like form extending from the lower end to the upper end of the web. The slit 11, heretofore referred to, is arranged between the inner side edges 80 of the webs 78, 79 for a portion of the length of said edges. Below the lower end of the slit 11 the inner side edges 80 of the webs 78, 79 are secured together by the stitching 83. The outer side edge of a web 78 and a web 79 are arranged between the sections of the front part 17, at the other side of the latter and are secured to said front part by the stitching 84, the outer side edge of the other web 78 and the other web 79 are arranged between the sections of the back part 20 at the other side of the latter and are secured to said back part 20 by the stitching 85. There is common to the webs 78, 79 an elastic reinforcing member 86 of tape-like form, which is arranged against the lower marginal portion of the faces of the web 79, which are to oppose the wearer. The member 86 is secured to the web 78 by the stitching 87. The stitchings 83 and the stitching 87 connects the web 78 to the web 79.

The inner section 77 of the side part 19 includes a pair of oppositely disposed webs 88, 89 of elastic woven material corresponding in width to and of less length than a web 78 or a web 79. The lower end of the web 88 inclines downwardly and outwardly. The lower end of the web 89 inclines downwardly and outwardly, but the inclination of the lower end of web 89 is greater than the inclination of the lower end of web 88. The material from which the webs 88 and

89 are formed corresponds to the material of the webs 78, 79. The webs 88, 89 align with the upper end of the webs 78, 79. The web 89 depends below the web 88.

There is correlated with the web 88 a set of spaced elastic combined fashioning and resistance increasing members of tape-like form which are disposed on that face of web 88, which is to oppose the wearer. The number of members of the set is four and are designated at 90, 91, 92, 93. The member 92 is disposed substantially horizontal. The member 93 is arranged below the member 92 and extends at a downward inclination from the inner to the outer side edge of and has its bottom edge flush with the lower end of the web 88. The member 91 is arranged directly over the member 92 and inclines upwardly from the inner side edge to the outer side edge of the web 88. The member 90 is arranged directly over the member 91 and inclines upwardly from the inner side edge to the outer side edge of and is disposed in spaced relation to the top edge of the web 88. That face of the web 88 provided with the elastic members has arranged throughout the upper marginal portion thereof, an elastic reinforcement 94 of tape-like form spaced from the member 90. The reinforcement 94 is secured to web 88 by stitching 95 and the latter also acts to secure the upper portion of a web 78, a web 79 and the web 88 together. The outer side edge of web 88 and the outer ends of the elastic members 90, 91, 92, 93 are disposed between the sections 21, 22 of the front part 17 at one side of the latter and are secured to the front part 17 by the stitching 84. The inner side edge of web 88 and the inner ends of the elastic members 90, 91, 92 and 93 are arranged between the upper portion of the web 79 and the upper portion of a reinforcing member 82 and which are secured to the said web 79 and member 82 by a stitching 83. The lower end edge of the web 88 is free.

There is correlated with that face of the web 89, which is to oppose the wearer, a set of spaced elastic combined fashioning and resistance increasing members of tape-like form which is oppositely disposed with respect to the other set of members referred to. The number of the set of members correlated with the web 89 is four and are designated at 96, 97, 98 and 99, and are secured to the web 89 by zig-zag stitching 100 and extend from the inner side edge to the outer side edge of the web. The member 96 is disposed horizontally and arranged in proximity to the upper end of the web 89. The member 97 is disposed directly below the member 96 and extends at a downward inclination from its inner to its outer end. The member 98 is arranged directly below the member 97 and extends at a downward inclination from its inner to its outer end and the member 99 is arranged directly below the member 98 and extends at a downward inclination from its inner to its outer end. The inclination of the member 98 is greater than the inclination of the member 97 and the inclination of the member 99 is greater than the inclination of the member 98. That face of the web 89 provided with the elastic members 96, 97, 98, 99 has arranged throughout the upper marginal portion thereof an elastic reinforcement 102 of tape-like form spaced from the member 96. The reinforcement 102 is secured to the web 89 by stitching 103 and the latter also acts to secure the other webs 78, 79 and the web 89 together. The outer side edge of the web 89 and the outer

ends of the elastic members 96, 97, 98, 99 are disposed between the sections 38, 39 of the back part 20 at one side of the latter and are secured to said part 20 by the stitching 85. The inner side edge of web 89 and the inner end of the members 96, 97, 98, 99 are arranged between the upper portion of the other web 79 and the upper portion of the reinforcing member 82 and are secured to such web and such member by the other stitching 81. The lower end edge of web 89 is free.

The simulation of the body of the wearer is indicated at 104. The lower edge of the garment has depending therefrom spaced supporters 105. The flap 12 constitutes means for protecting the body of the wearer from the slide fastener means. The webs 59, 60, 88, 89 constitute carriers for the combined elastic and restraining members secured thereto.

What I claim is:

1. In a garment for women's wear a body structure of girdle-like form including a pair of sides each formed of a fashioned elastic outer section, a fashioned elastic inner section and an elastic carrier means disposed inwardly of said inner section and connected at its sides and top with said sections, said carrier means being of less length than said sections, and spaced elastic resistance means disposed on one face of said elastic carrier means.

2. In a garment for women's wear a body structure of girdle-like form including a pair of sides each formed of a fashioned elastic outer section, a fashioned elastic inner section and an elastic element disposed inwardly of said inner section and connected at its sides and top with said sections, and oppositely disposed sets of spaced elastic resistance members secured to one face of said element.

3. In a garment for women's wear a body structure of girdle-like form including a pair of sides each formed of a fashioned elastic outer section, a fashioned elastic inner section and an elastic carrier means disposed inwardly of said inner section and connected at its sides and top with said sections, said carrier means being of less length than said sections, spaced elastic resistance means disposed on one face of said carrier means, an elastic reinforcing means common to and secured with said sections and carrier means, said elastic reinforcing means being disposed against the upper part of said carrier means, and an elastic reinforcing means common to and secured with said sections and being disposed against the lower part of said inner section.

4. In a garment for women's wear a body structure of girdle-like form including a pair of sides each formed of a fashioned elastic outer section, a fashioned elastic inner section and a pair of elastic elements disposed inwardly of said inner section and connected at the sides and top thereof with said sections, said elements being of less length than said sections, spaced elastic resistance means carried on one face of each of said elements, an elastic reinforcing means common to and secured with said sections and elements, said elastic reinforcing means being disposed against the upper part of said elements, an elastic reinforcing means common to and secured with said sections and being disposed against the lower part of said inner section, and oppositely disposed sets of spaced elastic resistance members secured against said elements.

5. In a garment for women's wear, a body structure of girdle-like form including a non-elastic back part, a front part having its major portion non-elastic and its remaining portion elastic, a pair of oppositely disposed elastic side parts interposed between and connected to the sides of said front and back parts, elastic elements correlated with, of less length than and opposing the inner face of a side part, said elements being connected at their top and sides to the side part of said body structure with which they correlate, and spaced elastic resistance means secured to one face of each of said elements.

6. In a garment for women's wear, a body structure of girdle-like form including a non-elastic back part, a front part having its major portion non-elastic and its remaining portion elastic, a pair of oppositely disposed elastic side parts interposed between and connected to the sides of said front and back parts, an elastic means correlated with, of less length than, opposing the inner face of and being connected at its top and sides to the side part of said body structure with which it correlates, and oppositely disposed sets of spaced elastic resistance members secured to one face of each of said means.

7. In a garment for women's wear, a body structure of girdle-like form including a non-elastic back part, a front part having its major portion non-elastic and its remaining portion elastic, a pair of oppositely disposed elastic side parts interposed between and connected to the sides of said front and back part, an elastic element correlated with, of less length than and opposing the inner face of a side part, said element being connected at its top and sides to the side part of said body structure with which it correlates, spaced elastic resistance means secured to one face of each of said elements, elastic reinforcing means common to and being secured to a side part and an element and being disposed against the upper part of the latter, and an elastic reinforcing means for and secured to each side part at the lower portion of the inner face of such parts.

8. In a garment for women's wear, a body structure of girdle-like form, a pair of oppositely disposed side parts each comprising an outer section formed of a pair of inner side edge aligned elastic webs, an inner section formed of a pair of inner side edge aligned elastic webs, a pair of rear inner side edge aligned elastic webs opposing the inner face of and of less length than said inner section, means for securing the webs of said sections together and the tops and sides of said rear webs to the webs of said inner section, and oppositely disposed sets of spaced elastic resistance members secured against one face of and extending from the inner side to the outer side of the said rear webs.

9. In a garment for women's wear, a body structure of girdle-like form, a pair of oppositely disposed side parts each comprising an outer section formed of a pair of inner side edge aligned elastic webs, an inner section formed of a pair of inner side edge aligned elastic webs, a pair of rear inner side edge aligned elastic webs opposing the inner face of and of less length than said inner section, means for securing the webs of said sections together and the tops and sides of said rear webs to the webs of said inner section, oppositely disposed sets of spaced elastic resistance members secured against one face of and

extending from the inner side to the outer side of the said rear webs, and an elastic reinforcing member of tape-like form disposed on the inner face of and extending from one end to the other end of each web of said inner section, said reinforcing members aligning with the inner side edges of the webs of said inner section and being secured to the said outer and inner sections.

10. In a garment for women's wear, a body structure of girdle-like form, a pair of oppositely disposed side parts each comprising an outer section formed of a pair of inner side edge aligned elastic webs, an inner section formed of a pair of inner side edge aligned elastic webs, a pair of rear inner side edge aligned elastic webs opposing the inner face of and of less length than said inner section, means for securing the webs of said sections together and the tops and sides of said rear webs to the webs of said inner section, oppositely disposed sets of spaced elastic resistance members secured against one face of and extending from the inner side to the outer side of the said rear webs, an elastic reinforcing member of tape-like form disposed on the inner face of and extending from one end to the other end of each web of said inner section, said reinforcing members aligning with the inner side edges of the webs of said inner section and being secured to the said outer and inner sections, elastic reinforcing means common to the said several webs, disposed against the upper part of the rear webs and being secured to the said several webs, and an elastic reinforcing means common to the webs of said outer and inner sections, disposed against the lower part of the webs of the inner section and being secured to the webs of the said sections.

11. In a garment for women's wear, a body structure of girdle-like form, a pair of oppositely disposed side parts each comprising an outer section formed of a pair of inner side edge aligned elastic webs, an inner section formed of a pair of inner side edge aligned elastic webs, a pair of rear inner side edge aligned elastic webs opposing the inner face of and of less length than said inner section, means for securing the webs of said sections together and the tops and sides of said rear webs to the webs of said inner section, and oppositely disposed sets of spaced elastic resistance members secured against one face of and extending from the inner side to the outer side of each rear web, one of the rear webs of a pair being of greater length than the other rear web of the pair.

12. In a garment for women's wear, a body structure of girdle-like form, a pair of oppositely disposed side parts each comprising an outer section formed of a pair of inner side edge aligned elastic webs, an inner section formed of a pair of inner side edge aligned elastic webs, a pair of rear inner side edge aligned elastic webs opposing the inner face of and of less length than said inner section, means for securing the webs of said sections together and the tops and sides of said rear webs to the webs of said inner section, oppositely disposed sets of spaced elastic resistance members secured against one face of and extending from the inner side to the outer side of each rear web, one of said side parts being formed with a slit of less length than and opening at its upper end at the top of said part, said slit being arranged between a portion of the length of the aligned inner side edges of the webs of said inner and outer sections and the entire length of the aligned inner side edges of the

rear webs correlated with such side part, means for securing the aligned inner side edges of the webs of said sections of such side part together below the inner end of the slit, and means on the front and inner faces of such side part for releasably closing said slit.

13. In a garment for women's wear, a body structure of girdle-like form having a front part, a back part, a pair of oppositely disposed side parts formed of fashioned elastic material and a pair of carriers formed of fashioned elastic material, each opposing the inner face of a side part and formed with a top, bottom and a pair of sides, said top and sides of each carrier being secured to a side part, said carriers being of less length than the side parts, and oppositely disposed sets of spaced elastic resistance members secured to one face of each carrier.

14. In a garment for women's wear, a body structure of girdle-like form having a front part,

a back part, a pair of oppositely disposed side parts formed of fashioned elastic material and a pair of carriers formed of fashioned elastic material, each opposing the inner face of a side part and formed with a top, bottom and a pair of sides, said top and sides of each carrier being secured to a side part, said carriers being of less length than the side parts, and oppositely disposed sets of spaced elastic resistance members secured to one face of each carrier, one of said carriers being formed of a pair of inner sidewise aligned spaced sections, that side part correlated with said sectional carrier being formed with a slit of less length than such side part, said slit opening at its upper end at the top of such part and depending below the sections of the sectional carrier, the space between the sections of the sectional carrier being aligned with a portion of the length of the slit.

PHILIP H. ROBBINS.
